B. C. MOXLEY

PORTABLE STEAM GENERATOR

Filed March 25, 1924

By

Jacobs & Jacobs Attorneys

UNITED STATES PATENT OFFICE.

BERRY C. MOXLEY, OF HOQUIAM, WASHINGTON.

PORTABLE STEAM GENERATOR.

Application filed March 25, 1924. Serial No. 701,797.

To all whom it may concern:

Be it known that BERRY C. MOXLEY, a citizen of the United States, residing at Hoquiam, in the county of Grays Harbor and State of Washington, has invented certain new and useful Improvements in Portable Steam Generators, of which the following is a specification.

This invention relates to new and useful improvements in devices for operating oil burners and is more particularly adapted to a portable steam generator for supplying steam to the oil burner used in conjunction with crude oil burning engines.

With the present system of boilers now in use in conjunction with the crude oil burners, it is necessary to keep the steam boilers going during the night when the engines are not in use in order to maintain a sufficient amount of steam so that the oil burner may properly operate the next morning for the purposes well known. This operation necessitates the employment of an attendant and also adds to the expense of the cost of the fuel used in order to keep the boilers hot. It is also necessary with a system of this character to allow the fires to die out so that the boilers may be cleaned out and when a new fire is needed difficulty is often experienced in getting the boilers heated in a short time for the reason that there is usually an insufficient draft suitable for the burning of the wood. With a device of my character, the loss of time and labor is obviated and the boiler with which my invention is connected may be heated in a comparatively short time and at a very low cost.

A still further object of my invention is to provide a portable steam generator which may be easily and quickly placed in position with the oil burner used in conjunction with the crude oil engine whereby a sufficient quantity of steam at the desired pressure may be raised, so that the oil can be sprayed into the boiler in the proper manner whereupon the boiler after the initial heating of the same will generate its own steam.

A still further object of the invention is to provide a portable steam generator of the above mentioned character, which is very simple in construction, strong and durable, and further well adapted for the purposes for which it is designated.

Other objects and advantages of this invention will become apparent during the course of the following description.

In the accompanying drawing forming a part of this specification and in which like numerals of reference designate like parts throughout the same,

Figure 1 is a side elevation of my invention showing the same connected with an oil burner, the latter being disposed within a boiler.

Figure 2 is a top plan view of the device.

Figure 3 is a vertical section of the steam generator, and

Figure 4 is a vertical section taken on line 4—4 of Figure 3.

In the drawing wherein for the purpose of illustration is shown the preferred embodiment of my invention, the numeral 1 designates the base or support upon which my steam generator is adapted to be mounted, and the latter comprises the substantially cylindrical casing 2, a flange 3 secured to the lower edge of the casing and extending therearound is adapted to be held in position on the base by means of the bolts 4, in the manner as clearly illustrated in the drawing. Disposed within the casing 2 adjacent the inner wall thereof is the water receptacle 5, the same being preferably tubular in cross section and having an angular extension formed at the upper end thereof as further illustrated by the numeral 6 in the drawing, the purpose of which will hereinafter be more fully described.

The water receptacle 5 has its lower end threaded onto the supporting base 7 and the outer end of the steam dome 6 or trap is also threaded onto the cap 8 in the manner as clearly illustrated in Fig. 3 of the drawing. Suitable brackets such as are shown at 9 are provided for the purpose of supporting the tubular water receptacle and steam dome 6 in proper position within the casing 2. With the construction shown in Fig. 3 of the drawing, it will thus be seen that a substantially inverted L-shaped container is provided wherein the longer arm forms the water chamber or receptacle and the shorter arm will form the steam trap.

Adapted to be associated with the water container and steam dome is the coil pipe 10, the upper end thereof being connected

2 to the steam dome while the opposite or lower end communicates with the lower portion of the water receptacle. The purpose of this coil pipe will also be presently apparent.

10 In order that water may be supplied to the water receptacle 5, a suitable pipe such as is shown at 11 in the drawing, extends through the casing 2 and into the lower portion of the water receptacle and the opposite end of the same is connected to a suitable source of supply, whereby water may be supplied to the water receptacle. A valve of any conventional type and such as is shown 15 at 12, is provided in the supply pipe 11 for the purpose of shutting off the supply of water to the water receptacle whenever necessary. The casing 2 is also adapted to support the water level gauge 13, the latter being in communication with the water receptacle 5 in the usual manner and for the purposes well known in the art.

20 Extending outwardly from the steam dome 6 and through one side of the casing 2, is the pipe 14 which supports the steam gauge 15. A safety valve 16 also extends upwardly from the steam dome 6 and through the casing 2 in the manner as shown in Fig. 3 of the drawing.

25 30 For the purpose of generating steam in the steam dome 6, I provide a suitable burner such as is shown at 17 in the drawing, the latter being adapted to be supported directly below the coil pipe 10. A fuel tank 35 18 is also supported on the base 1 and has a fuel pipe 19 extending therefrom and in communication with the burner 17 for supplying the proper amount of fuel to the burner whereby the latter may properly operate. In the present instance I desire to 40 use kerosene as the fuel for the purpose of generating steam, although it is to be understood that any other suitable fuel may be used in place thereof. Access to the burner 45 17 may be had through a suitable door 20 which is provided in the casing 2.

The operation of my steam generator may be briefly stated as follows:

50 With the water in the water receptacle 5 up to the level shown in Fig. 3 of the drawing, the heater 17 is ignited and thus will cause the coil pipe 10 to be heated in such a manner as to generate a sufficient quantity 55 of steam within the angular extension formed on the upper end of the water receptacle, it being understood that the water in the pipe 10 will not be discharged through the upper end thereof into the steam dome. 60 The steam thus generated in the steam trap or dome 6 will be then discharged through the suitable outlet pipe 21 which extends from the upper portion of the steam trap or dome, and through the top of the casing 2, into the outlet pipe 22. The latter is 65 connected at its outer end to the burner pipe

23 which may be of any conventional construction, and as is well known in the art, the same is provided with the oil supply pipe 24 and the burner head 25. With a construction of this kind it will be readily seen that a supply of oil from the pipe 24 and steam from the pipe 22 will be admitted to the burner whereby the same will be sprayed into the boiler for the purpose of heating the same whereby the latter will 75 be caused to operate and further generate steam sufficient to cause the operation of the engine to which the same is connected. A suitable valve 26 is provided in the outlet pipe 21 for cutting off the supply of 80 steam to the burner as the case necessitates. It is also to be understood that when the desired pressure has been reached and sufficient steam has been caused to be generated in the steam dome 6, the heater 17 will be 85 shut off.

In order to render my device portable, I provide a suitable handle 27 on the top of the casing and as the entire device is very light the same may be easily transported 90 from place to place without much difficulty.

It will thus be seen from the foregoing description, that a steam generator has been provided which is very simple in construction, inexpensive, and further of such construction as to enable the same to be readily placed in operation and will properly heat the boiler in a minimum amount of time by supplying the desired generated steam to the same in connection with the oil burner, so that loss of labor and time is obviated and the necessity of having to employ an attendant to watch the same is also done away with.

From the foregoing description of the 105 construction of my improved apparatus, it will be seen that I have provided a simple, inexpensive and efficient means for carrying out the objects of the invention, and while I have particularly described the elements 110 best adapted to perform the functions set forth, it is obvious that various changes in form, proportion, and in the minor details of construction may be resorted to, without departing from the spirit or sacrificing any 115 of the principles of the invention.

Having thus described my invention, what I claim is:

A steam generator comprising a casing, 120 a water receptacle having angularly disposed end portions one end portion being vertically disposed in the casing and the other end portion horizontally disposed in the casing, one vertical wall of the vertically disposed end portion engaging one side of the casing and the end wall of the horizontally disposed end portion engaging the opposite side of the casing, the surface of the casing being spaced from the remaining side portion of the water receptacle to form a com- 125 130

bustion and heating chamber, a coil located in the combustion chamber and connected at one end with the lower portion of the vertically disposed end portion of the water receptacle and connected at its other end with the end portion of the horizontally disposed end of the water receptacle, a heater located in the combustion chamber below the coil,

a water inlet pipe connected with the lower portion of the vertically disposed end of the water receptacle and a steam outlet pipe connected with the upper portion of the horizontally disposed end portion of the water receptacle. 10

In testimony whereof I affix my signature.
BERRY C. MOXLEY.
